UNITED STATES PATENT OFFICE.

HENRY McLAREN, OF LEEDS, COUNTY OF YORK, ENGLAND.

DEVICE FOR REDUCING THE PRESSURE OF LIQUIDS.

SPECIFICATION forming part of Letters Patent No. 393,021, dated November 20, 1888.

Application filed January 10, 1888. Serial No. 260,334. (No model.)

To all whom it may concern:

Be it known that I, HENRY McLAREN, a subject of the Queen of Great Britain, and a resident of Leeds, in the county of York, England, 5 have invented certain new and useful Improvements in Devices for Reducing the Pressure of Liquids, of which the following is a specification.

My invention relates to that class of devices 10 in which a valve is counterbalanced, so as to regulate the passage of steam or other fluid from a high-pressure pipe or chamber to another pipe or chamber in which the fluid should be retained or discharged at a lower pressure; 15 and my invention consists of a device having the parts constructed and arranged to operate as fully set forth hereinafter and as illustrated in the accompanying drawings, in which—

Figure 1 is a longitudinal sectional elevation 20 of a pressure-reducing device embodying my invention; Fig. 2, a transverse sectional elevation.

The casing A of the device, as shown, consists of a rectangular sealed box, 20, with a 25 tubular branch, 21, at one end having a reduced terminal inlet-port, a, with a surrounding seat for a valve, Q. The opposite end of the box is closed by a detachable head, 22, with a hollow tubular extension, 23, and a packing-box, 24, 30 in which latter turns a screw-rod, 25, provided with an operating hand-wheel, 26. From the lower side of the box extend two hollow branches, d 10, the former with a bore or socket receiving a sliding plug or piston, 3, and the latter with a discharge-opening to receive a 35 plug or piston-valve, C, controlling the flow from the casing to the discharge branch d through the outlet-port b and byway-passage 12. The upper end of the stems of the piston 40 and valve slide in bearings in screw-plugs 31 32, fitting threaded openings in the top of the box, and each stem is slotted for the passage of a lever pivoted to the piston-stem and having a sliding bearing on the valve-stem and 45 upon an intermediate fulcrum, k. The fulcrum k is preferably movable to vary the leverage, and, as shown, is a projection upon a sliding bar formed at one end into the valve Q and with a threaded socket at the other to receive 50 the threaded end of the rod 25, feathers 33 extending into longitudinal slots in the bar and

preventing the turning of the bar. By turning the screw-rod 25 the bar 7 can be moved back and forth and the fulcrum brought to any desired position in respect to the lever B, the 55 valve Q, as the bar 7 is drawn back to alter the leverage, being opened to admit the steam or other fluid under full pressure.

The plugs or piston and valve 3 C are of the same area, and consequently the pressure on 60 both is the same, and when the fulcrum k is midway between the bearings of the plug-stems the two will be exactly counterbalanced and they are in equipoise; but on the movement of the fulcrum the equilibrium is disturbed, and although the pressure on each is the same the one farthest from the fulcrum has the advantage of increased leverage over the other, which latter therefore rises under the superior power exerted by the former, 70 which descends.

When the valve Q is opened to admit the fluid to the casing, the fulcrum k moves to the left and the valve 3 has then the greatest leverage and will descend until the byport 12 is 75 more or less opened and a part of the fluid escapes to the discharge, the descent of the plug or valve 3 closing a channel, 15, leading from the branch d to the branch 10. The pressure in the pipes or chambers with which the device 80 communicates through the branch d acts of course upon the lower side of the plug 3, and as soon as it accumulates sufficiently to balance the difference in the leverage the equilibrium will be restored and the two plugs 85 will take the position shown in Fig. 1, closing the communication through the port b.

Supposing the area of the plugs to be one square inch and the distance of their bearings to be two inches, with a fluid-pressure of one 90 hundred pounds in the casing, and the fulcrum to be exactly in the center, the two plugs will be in equilibrium; but supposing the fulcrum to be moved half an inch to the left, the equilibrium will be disturbed and the plug or valve 95 3 will at once be depressed and the piston C will be raised until when the pressure beyond and below the valve 3 rises to sixty-six and two - thirds pounds, being two - thirds the pressure in the casing, it will counteract 100 the effects of the excess of leverage in favor of the valve-plug 3, and the equilibrium will

be restored, the valve will rise, the piston descend, and the port *b* will be closed. Upon any decrease of pressure below the valve 3, from condensation or otherwise, the preponderance of pressure will be above the valve and will force down the same and open the port *b*, so as to admit additional fluid below the valve and restore the equilibrium. By this means any desired variation of pressure may be maintained upon the opposite sides of the valve 3. By moving the fulcrum *k* the relative pressures above and below the valve 3 may be varied at will, and this adjustment can be effected from without the case without the necessity of opening the latter.

When it is desired to release the pressure from the outlet-opening or the receiver, it is only necessary to move the fulcrum in the direction to close the inlet-valve *Q*, when the piston or waste-plug *C* not only obtains the advantage of a leverage over the outlet-valve, but is further assisted by the pressure already on the under side of the outlet-valve. The waste-plug or piston is then instantly depressed and the outlet-valve raised until it opens the exhaust-passage 15, which opens up a communication between the outlet-pipe or the receiver with which it is connected and the exhaust-pipe by which the fluid escapes and the pressure in the outlet is relieved.

When the valve *Q* for inlet of fluid to the casing is on its seat and the device is at rest, the fulcrum *k* may be a little nearer the valve 3 of the outlet, so that any pressure which may be in the casing or in the outlet serves to depress the plug of the discharge and tends to prevent any leakage from the casing in the event of the inlet-valve to the same not being properly seated.

I do not here claim any of the features shown and claimed in my application for Letters Patent, Serial No. 260,333.

Without limiting myself to the precise con-

struction and arrangement of parts shown, I claim—

45

1. The combination, in a device for reducing pressure, of a sealed casing having an inlet and sockets for two reciprocating plugs, one constituting a piston, the other a reducing-valve, and a lever connecting the stems of the plugs and resting on an adjustable fulcrum, substantially as described.

50

2. The casing *A*, having an inlet-port, outlet-port, and discharge branch, socket receiving a movable plug or piston, and by-channel connecting with the discharge-opening, in combination with a valve adapted to the discharge-opening, connected with a lever also connected with said piston, and a movable fulcrum for said lever, substantially as described.

60

3. The sealed casing, with its inlet-port and discharge branch and waste branch and passages 12 15, in combination with the piston and valve-plugs, connecting-lever, and movable fulcrum, substantially as described.

65

4. The combination of the sealed casing, inlet and discharge ports, piston, and reducing-valve, lever connecting the said valve and piston, and a bar carrying the fulcrum of the piston and formed into a valve adapted to the inlet-port, substantially as described.

70

5. The combination, with the piston and reducing-valve and connecting-lever arranged in a sealed casing, of a movable bar, 7, carrying the fulcrum of the lever, and socket to receive a screw-spindle turning in a bearing in the casing, substantially as set forth.

5

In testimony whereof I have signed my name to this specification in the presence of two subscribing witnesses.

HENRY McLAREN.
